UNITED STATES PATENT OFFICE

94,402

DESIGN FOR A COMBINED RANGE LAMP, SHELF, AND INTERMEDIATE MEMBER

Almer H. Brodbeck, St. Louis, Mo., assignor to
American Stove Company, St. Louis, Mo., a
corporation of New Jersey

Application May 31, 1934, Serial No. 51,981

Term of patent 14 years

To all whom it may concern:

Be it known that I, Almer H. Brodbeck, a citizen of the United States, residing at St. Louis, in the State of Missouri, have invented a new, original, and ornamental Design for a Combined Range Lamp, Shelf, and Intermediate Member, of which the following is a specification, reference being had therein to the accompanying drawing.

The accompanying drawing is a perspective view of my design of a combined range lamp, shelf and intermediate member, the rear panel of the range being shown in dotted lines to show the association of the design with a range.

The predominant features of my new design

comprise two upwardly extending parallel members having at their upper ends a combined horizontal lamp, a horizontal shelf through which said members pass and located above the lower ends of the upwardly extending members, and a horizontal member shaped as shown located between the shelf and lamp.

I claim:

The ornamental design for a combined range lamp, shelf and intermediate member, as shown and described.

In testimony whereof, I hereto affix my signature.

ALMER H. BRODBECK.
